ELECTRIC PLUG

Alexander Carlino, Cleveland, Ohio

Application September 23, 1936, Serial No. 102,213

1 Claim. (Cl. 173—343)

This invention relates to connectors for electrical circuits and more particularly to a plug capable of swiveling about its longitudinal axis so as to relieve twisting strains on the associated cord.

The ordinary plug used with portable electrical devices, such as irons, fans, electric drills and the like, is incapable of swiveling movement when inserted in the wall or lamp socket. Consequently, as the electrical device is moved about while still plugged in the socket, particularly in the case of an electric curling iron, the insulation on the cord, at the point where it enters the plug, becomes frayed due to the twisting or torsional strains imparted thereto by such use. In time the bare wires may be exposed, causing a dangerous fire hazard and necessitating replacement of the cord.

One object of my invention is the provision of a swivel joint between the two parts of the plug assembly whereby the part connected with the cord may rotate freely about its longitudinal axis and still remain in electrical contact with the stationary part of the plug. Another object of my invention is a novel plug construction in which a spring contact is maintained between the two contact points on the stationary and movable parts of the assembly. A still further object comprises means for breaking the electrical circuit upon separation of the two parts of the plug in such a manner that any arcing that occurs will take place inside the plug, thus eliminating the possibility of fire or shock.

Other objects and advantages will be apparent from the following detailed description and drawing of an embodiment of my invention, in which:

Figure 1 is a longitudinal sectional view through a plug assembly embodying my invention.

Figure 2 is a transverse sectional view taken through the assembly on line 2—2 of Fig. 1.

Figure 3 is a plan view of the movable part of the plug.

Figure 4 is a transverse sectional view taken on line 4—4 of Fig. 1, and

Figure 5 is a longitudinal sectional view of a modification of the stationary member.

Referring to Figs. 1 to 4, there is shown a member 10 of insulating material provided with a threaded metallic element 11 adapted to be screwed into a lamp or wall socket. Member 10 may be recessed, as at 12, and a portion 13 of element 11 bent into the recess to assist in holding the element in position.

One of the electrical contacts in member 10

comprises a helical spring 14 mounted in a circular groove 15 in the member. The spring is made of flat resilient material and is provided with an extension 16 which passes through an opening 17 in member 10 and slot 18 in element 11. The extension may be soldered or otherwise secured to element 11 so as to form a good electrical connection.

At the center of member 10 is a recess 19 adapted to receive the contact for the other side of the circuit. A guide and locking member 20 is formed in the shape of a U in such a manner that the bottom of the U engages the bottom of recess 19, and the sides of the U engage a pair of opposite side walls of the recess. Adjacent the outer surface 21 of member 10 each arm of the U-shaped member 20 is bent in a reverse direction, as at 22, and extends part way into recess 19 where the ends of portions 22 are bent towards each other to form locking shoulders 23. Inside of member 20 and lying against the bottom and side walls thereof is an insulating member 24 which separates member 20 from a contact element 25. Said latter element is made of spring material and comprises a bottom wall 26 and arms 27. Openings are provided in members 20 and 24, and wall 26 of element 25 is threaded, to receive a bolt 28 that holds the parts in assembled relation. It will be noted that the opening in member 20 is considerable larger in diameter than the bolt, so as to prevent contact between such member and the bolt. An insulating disc 29 is positioned between an enlarged head 30 of bolt 28 and the turned over portion 31 of contact element 11 to thereby separate the bolt 35 from said element.

The movable or swivel member of the plug assembly comprises a block 32 of insulating material provided with an opening 33 receiving the two wire conduit or cord (not shown) connected 40 to the electrical device. The block is recessed at 34 to receive the bases of the contact prongs 35 and 36. Prong 35 is formed with a base 37 and is assembled with block 32 in such a manner that the prong is positioned substantially the same 45 distance from the longitudinal center line of the plug assembly as is the groove 15. Prong 36 is cylindrical in shape and is likewise formed with a base 38, but an extension 39 thereon positions the prong at the center of block 32. Bases 37, 38, 50 and hence the prongs, are held in position by bolts or rivets 40, 40 which may either be secured into threaded holes in block 32 or assembled with the latter as it is being molded into the desired shape. The bases are provided with the usual 55

threaded holes for bolts 41 by which the ends of the cord are connected to the contacts.

Connection between the two parts of the plug assembly is made by inserting prong 36 between arms 22 of member 20 until the locking shoulders 23 enter a circular groove 42 at the end of the prong. Arms 22 normally tend to spring towards each other, and in moving prong 36 into position the arms are forced apart so that shoulders 23 are held in groove 42 by the tension in the arms. By the time the prong is locked in position the extreme end thereof has engaged arms 27 of contact element 28. Arms 27 also normally tend to spring towards each other, and are forced apart by the tapered end 43 of the prong so that a good connection is assured by means of the inward pressure of arms 27. It will be noted that arms 22 are provided with arcuate wings 44 which serve to position prong 36 centrally of the plug and guide it in place. Locking shoulders 23 are shown recessed, as at 45, to conform to curvature of prong 36 so as to partially surround the latter member.

As prong 36 passes between arms 22, and before it reaches contact 28, prong 35 engages the outer surface of spring 14. Further movement of prong 35 towards member 10 compresses the spring 14 and provides an electric contact under spring pressure. It will thus be apparent from the above description that block 32 is free to rotate relative to member 10 while at all times a firm engagement between the contacts is maintained.

In Fig. 5 there is shown a stationary part similar to member 10 but with an end formed for use with a common slip-in type of socket. The member 50 is provided with a groove 51 and recess 52, the same as groove 15 and recess 16 respectively of Fig. 1. Spring 53 is shown in its extended position since the movable half of the plug is not in place. Connection between the spring and one side of the live circuit in the base socket is effected by means of an element 54 which passes through a slot in member 50 and projects a considerable distance beyond said member. Element 54 is bent at one end, as at 55, to form a stop which engages spring 53 at the bottom of groove 51. Spring 53 is soldered or otherwise secured to the bent portion 55. Element 54 may be simply and effectively secured in member 50 by bending over a portion 56 thereof into a recess 57 of said member. Thus, movement in one direction is prevented by bent portion 55 and in the other direction by portion 56.

In groove 52 are mounted a guide member 58 and contact element 59 separated by an insulating member 60 corresponding to like parts of Fig. 1. Contact element 59 is mounted in a slot 62 in member 50 and projects outwardly the same distance as element 54 to connect the plug with the other side of the circuit. Bolt 63 electrically joins elements 59 and 58 and serves to hold these parts as well as members 58 and 60 in assembled relation.

In Fig. 5 the arms 54 of member 50 are shown bent towards each other until guide wings 55

touch. In this manner added spring action is given the arms when the movable prong 36 is pushed in position, causing the locking shoulders 23 (Fig. 1) to snap into groove 42 to hold the parts locked together.

Thus it will be apparent that my invention provides a swivel joint between the two parts of the plug so that the part to which the cord is attached may rotate and thus relieve the cord from twisting strains. Furthermore, the plug may advantageously be used in ceiling sockets since the locking means holds the assembly firmly together and prevents the movable member from dropping out. In addition the spring engagement of the contact members assures a good electrical connection. It will also be observed that in breaking the circuit, which is the time at which arcing usually occurs, the central prong 36 separates from contact element 27 or 59 before prong 35 leaves the spring 14 or 53. In this manner any arcing will take place inside the member and eliminate the danger of fire or shock. Moreover, it will be apparent that since the guide member 22 or 58 is separated from its associated contact element and retaining bolt, the guide member forms no part of the electric circuit when the movable part of the assembly is withdrawn. In this manner danger of shock or short circuit is still further reduced to a minimum.

While I have shown and described my invention in conjunction with a plug adapted to be inserted into a lamp or wall socket, it will be understood that the stationary part of the assembly may be incorporated in a base socket or wall outlet so that it may be fixedly mounted in the wall. The movable part of the assembly would, in such case, cooperate directly with the outlet.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

An electrical connector comprising a pair of detachable members, one of said members having a longitudinally disposed recess and a groove spaced from and surrounding said recess, a helical spring contact element in said groove, a contact element at the inner end of said recess, guiding means in said recess having a pair of longitudinally disposed arms, the other of said members having a pair of metallic prongs adapted to be inserted in said groove and recess and engage said contact elements, said spring being adapted to exert outward pressure against one of said prongs, and means at the end of one of said arms adapted to enter a groove in the other of said prongs substantially simultaneously with the engagement of said other prong with its respective contact element to hold said members in electrical engagement.

ALEXANDER CARLINO. 65
